LOCKING HANDLE FOR SASH

Harry M. Riegelman, Rolling Hills, Calif., assignor to
Ador Corporation, Fullerton, Calif., a corporation of
California

Filed Feb. 7, 1964, Ser. No. 343,398
11 Claims. (Cl. 292—129)

This invention relates generally to sliding closure members, and more particularly to a new and useful locking handle for sliding sash members such as doors, windows and the like.

Laterally sliding closure members, such as glass doors, screens, etc., are normally provided with an inside lock which can be operated to prevent the closure member from being opened from the outside. It has also been common practice to provide the sliding sash with an inside handle so that, when the sash is unlocked, it can be readily moved to an open position.

Although the sliding sash lock and handle arrangements of the prior art have generally served their purposes, they have left much to be desired in the way of simplicity of structural arrangement, economy, durability, ease of adjustment after installation upon the sash, and provision of adequate means for indicating whether or not the sash is locked or unlocked without requiring close proximity observation of the lock. In this latter connection, it would be a matter of great convenience if persons on the outside could determine from a distance whether or not a sliding door is locked, without having to actually approach and attempt to open the door.

Accordingly, it is an object of the present invention to provide a new and improved locking handle construction which overcomes the above and other disadvantages of the prior art.

Another object is to provide a new and improved locking handle for a sliding sash, wherein the locking handle is easily adjustable after installation to any desired vertical position along the sash.

A further object of the invention is the provision of a new and improved locking handle, wherein the latched or unlatched state of the sash is readily ascertainable from either side of the sash by direct observation from a considerable distance.

Still another object is to provide a new and improved locking handle for a sliding sash, wherein the latch plate of the lock also serves as a handle.

Yet another object of the present invention is the provision of a new and improved locking handle which is extremely durable and reliable in operation.

A still further object is to provide a new and improved adjustable locking handle satisfying all of the foregoing objects, yet being of relatively simple and economical structural design.

The above and other objects and advantages of this invention will become apparent from the following description, when taken in conjunction with the accompanying drawings of a presently preferred embodiment thereof, and wherein:

FIGURE 1 is an elevational view, from the inside looking out, of a sliding screen door mounted in the casing of a window and embodying the locking handle of the present invention;

FIGURE 2 is an enlarged, fragmentary elevational view, a portion being broken away, of the area 2 in FIGURE 1, and illustrates the cooperation between the locking handle and the jamb of the window casing when the screen door is locked;

2

FIGURE 3 is a fragmentary sectional view, taken along the line 3—3 in FIGURE 2, and also illustrates the locking handle in the locked position;

FIGURE 4 is a view similar to FIGURE 3, and illustrates the door in the unlocked state, with the latch plate being used as a handle;

FIGURE 5 is an exploded perspective view of a locking handle in accordance with the invention;

FIGURE 6 is an elevational view, taken in the direction of the arrow 6 in FIGURE 5, of the pivot and mounting block of the locking handle; and

FIGURE 7 is a sectional view, taken along the line 7—7 in FIGURE 5, and illustrating the construction of the pivot and mounting block at each of its ends.

Referring now to the drawings, and particularly to FIGURE 1 thereof, there is shown a window casing 10 installed in an opening in a wall 12 in the usual manner employed in the art. The casing 10 is preferably fabricated from extruded aluminum frame members which are suitably formed to provide cooperating flanges, ridges and channels for engaging and accommodating the sashes of a movable window member 14, a fixed window member (not shown) and a sliding screen door 16. Of course, it will be appreciated by those of ordinary skill in the art that the construction is not limited to windows or sliding screen doors, but is equally applicable to all openings which utilize a sliding closure member in a casing. For purposes of description, however, the construction shown in the drawings depicts a sliding screen door in a window construction.

The sliding screen door 16 has a sash frame which is also preferably fabricated from extruded aluminum frame members including left and right stile members 18, 20 and upper and lower rail members 22, 24, respectively.

The sash of the sliding screen door 16 mounts a wire screen 26 by means of a continuous locking strip 28, of plastic or the like, which is pressed into the recess formed by a beaded flange 30 along the inner periphery of each of the sash frame members, to lock the edges of the wire screen 26 firmly in place (FIGURES 2—4).

The movable window member 14 is provided with a handle 32 and lock 34 of a type well known in the art. In contrast, the sliding screen door 16 embodies a new and improved, adjustable locking handle 36 in accordance with the present invention.

Referring now more particularly to FIGURES 2—7, the structure and operation of the locking handle 36 will become apparent. The locking handle 36 includes a combination handle and latch plate 38 and a combination mounting and pivot block 40 for the plate 38.

The mounting block 40, which is preferably fabricated of plastic or the like, is mounted in sliding engagement with the stile 20 of the screen door 16. To this end, the mounting block 40 is seated and rides within a channel 42 defined by walls 20a, 20b and a flange 20c of the stile 20. In order to retain the mounting block 40 within the channel 42, the wall 20d of the stile extends just slightly beyond the wall 20b to overlie the open side of the channel 42. When the mounting block 40 is installed within the channel 42, this projection of the wall 20d also overlies a pair of shoulders 44 which are provided, one at each end, upon the mounting block.

A pair of elongated retaining slots 46 are provided in the left side of the mounting block 40 to receive the ends of a bowed spring member 48. When the mounting block 40 is to be installed within the channel 42, the right

side of the block having shoulders 44 is first moved into place behind the projecting portion of the stile wall 20d. The mounting block 40 is then pivoted about the shoulders 44 to move it into the channel 42. At the same time, the bow spring 48 is deformed inwardly towards the mounting block and rides over a retaining lip or bead 40 projecting from the flange 20c into the channel 42. After the bowed spring 48 has cleared the bead 40, it immediately expands behind the bead to lock the mounting block 40 within the channel 42.

By virtue of the sliding engagement of the mounting block 40 with the stile walls defining the channel 42, the entire locking handle assembly 36 can be readily adjusted to any desired vertical position along the stile 20. Hence, if it is desired to prevent the screen door 16 from being unlocked by a short person, such as a child, the mounting block 40 for the locking handle would be moved along the stile 20 to a relatively high vertical position. On the other hand, where it is desired that the locking handle 36 be used by shorter persons, the entire assembly can easily be relocated by sliding the mounting block downward within the channel 42 to any convenient lower position along the stile 20.

The combined latch plate and handle 38 is preferably fabricated of a strong metal material such as aluminum, steel or the like. As best observed in FIGURE 4, the latch plate 38 comprises a combined handle grip and lock catch portion 38a integrally formed at one end, a hollow elongated sleeve 38b formed at the other end, and a substantially planar intermediate portion 38c.

The latch plate 38 is secured to the mounting and pivot block 40 by a novel, spring-loaded hinge arrangement. In this connection, a resilient, laterally deformable pivot post is provided, rather than a conventional hinge pin which is solid and relatively non-deformable. To this end, a pair of coaxial springs 52, 54 are placed within the opening 56 defined by the sleeve 38b, in end-to-end abutment, and thus provide the desired resilient pivot post. In mounting the latch plate 38 to the mounting block 40, both springs 52, 54 are axially compressed within the sleeve 38b and then allowed to expand into upper and lower apertures or sockets 48, 60 provided at the upper and lower ends, respectively, of the mounting and pivot block 40. In this connection, the outer tail ends 52a, 54a of the springs 52, 54 are received within appropriate slots 62, 64 branching from the upper and lower sockets 48, 60, respectively, to resist rotation of the springs about their common longitudinal axis.

The inner tail ends 52b, 54b of the springs 52, 54, respectively, extend through a clearance opening 66 in the sleeve 38b and abut the face of the intermediate portion 38c of the latch plate 38 (FIGURES 2-4). Hence, the compression springs 52, 54 also behave as torsion springs to apply torque, via the tail ends 52b, 54b, to the handle and latch plate 38. In this connection, the coils springs 52, 54 must be wound in opposite directions so that, in the illustrated configuration, they will apply torque to the plate 38 in the same direction.

As best observed in FIGURES 2-4, the handle grip and lock catch 38a is provided with a plurality of parallel, elongated teeth 68. These teeth are adapted to engage a bead 70 projecting inwardly from the right jamb 72 of the window casing 10, and the bead 70 also extends parallel to the teeth 68. To further enhance the locking cooperation between the teeth 48 and the jamb bead 70, the teeth are canted slightly with respect to the plane of the latch plate 38.

Referring now to FIGURE 3, it will be apparent that, in order to lock the screen door 16, it is merely necessary to overcome the biasing forces of the springs 52, 54 and pivot the latch plate 38 to a position whereby one of the teeth 68 will engage the jamb bead 70. Once this has been done, the springs 52, 54 bias the latch plate 38 against the jamb 72, so that one of the teeth 68 will re-

5

main in locking engagement with the jamb bead 70 until deliberate action is taken to override the spring forces and bring about disengagement of the latch plate from the jamb. This latter action can be accomplished only from the inside of the screen door and, hence, the locking arrangement is essentially tamper-proof from the outside. By providing a multiplicity of parallel teeth 68, the screen door 16 can be locked in any one of a plurality of closely adjacent positions. Moreover, the provision of a plurality of teeth 68 insures that the screen door can always be locked in the fully closed position of FIGURE 3 regardless of the degree of warpage or bowing of the jamb 72.

The aforescribed latching arrangement is extremely strong and durable, and does not depend for its strength upon the mounting block 40 or the springs 52, 54. In this connection, if any attempt is made to slide the screen door 16 open when it is latched as shown in FIGURE 3, the stress will initially be taken by the resilient pivot post assembly provided by the springs 52, 54. However, as the stress builds up and the springs deform laterally, the innermost face of the sleeve 38b of the latch plate comes into direct contact with the wall 20b of the right stile 20. Hence, no additional stress, beyond that necessary for slight lateral deformation of the springs 52, 54, is borne by either the springs or the mounting block 40.

Referring now to FIGURE 4, the manner in which the latch plate 38 is used as a handle for opening and closing the screen door 16 will be apparent. When the latch plate 38 is pivoted to disengage the teeth 68 from the jamb bead 70 in FIGURE 3, and the screen door 16 is moved to the left to allow the latch plate to clear the jamb 72, the springs 52, 54 automatically rotate the latch plate into a nonlatching storage position against the screen 26, approximately 180° away from the latching position of FIGURE 3. With the latch plate 38 in this storage position, the handle grip portion 38a projects beyond the inner peripheral border of the stile 20 and is readily observable from either side of the screen door 16 as a clear indication that the sliding door is unlocked. Moreover, the handle grip portion 38a or intermediate portion 38c of the latch plate may be grasped by the hand as a convenient handle for sliding the screen door 16 in either direction once the door has been unlocked.

It will be apparent from the foregoing that, while a particular form of my invention has been illustrated and described, various modifications can be made without departing from the spirit and scope of my invention. Accordingly, I do not intend that my invention be limited, except as by the appended claims.

I claim:

1. In combination with a casing having head and sill members and a pair of jambs and a sliding sash including upper and lower rails and a pair of stiles, a latch mechanism comprising:
a handle member pivotally mounted upon one of said stiles;
means embodied by said handle member for selectively engaging in a first position of said handle member one of said jambs to prevent sliding movement of said sash relative to said casing;
and means for spring-biasing said handle member to a second position out of engagement with said one of said jambs and projecting beyond the inner peripheral border of said one of said stiles, whereby said handle member is visible from either side of said sash.
2. In combination with a casing having head and sill members and a pair of jambs and a sliding sash including upper and lower rails and a pair of stiles, a latch mechanism comprising:
a substantially planar handle mounted upon said sash in sliding engagement with one of said stiles;
means for pivoting said handle about an axis parallel to said one of said stiles;
means integrally embodied by said handle for selectively engaging in a first pivotal position of said handle one

of said jambs to prevent sliding movement of said sash relative to said casing; and means for spring-biasing said handle to a second pivotal position out of engagement with said one of said jambs so that at least a portion of said handle is readily visible from either side of said sash. 5

3. In combination with a casing having head and sill members and a pair of jambs and a sliding sash including upper and lower rails and a pair of stiles, a latch mechanism comprising:

a handle pivotally mounted upon one of said stiles; locking means integral with said handle for selectively engaging in a first pivotal position of said handle one of said jambs to prevent relative movement between said sash and said casing; and means for biasing said handle to a second pivotal position approximately 180° away from said first pivotal position and projecting beyond the inner peripheral border of said one of said stiles, whereby said handle is visible from either side of said sash to indicate lack of engagement between said locking means and said one of said jambs. 15

4. In combination with a casing having head and sill members and a pair of jambs and a sliding sash including upper and lower rails and a pair of stiles, a latch mechanism comprising:

a latch plate carried upon one of said stiles; means embodied by one of said jambs of said casing for selectively engaging a portion of said latch plate to restrain said sliding sash against movement relative to said casing; a flexible pivot post passing through said latch plate and spring-biasing said latch plate to a position approximately 180° away from the position in which said latch plate engages said one of said jambs; and means embodied by said latch plate for limiting the lateral stresses borne by said flexible pivot post and for bearing all of the stresses above said limit. 30

5. In combination with a casing having head and sill members and a pair of jambs and a sliding sash including upper and lower rails and a pair of stiles, a latch mechanism comprising:

a mounting block secured to one of said stiles; a latch plate; an integral sleeve at one end of said latch plate; a combined handle grip and lock catch at the other end of said latch plate and integral therewith; flange means embodied by one of said jambs of said casing for selectively engaging said handle grip and lock catch carried at the end of said latch plate to restrain said sliding sash against movement relative to said casing; and spring means extending through said sleeve and pivotally securing said latch plate to said mounting block, said spring means biasing said latch plate towards a position approximately 180° away from the position of said latch plate wherein said handle grip and lock catch of said latch plate are in engagement with said flange means, the orientation of said spring means within said sleeve being such that said sleeve abuts said one of said stiles upon lateral distortion of said spring means. 55

6. In combination with a casing having head and sill members and a pair of jambs and a sliding sash including upper and lower rails and a pair of stiles, a latch mechanism comprising:

a mounting block; means for securing said mounting block to one of said stiles in sliding engagement therewith; a latch plate; an integral lock catch at one end of said latch plate; flange means embodied by one of said jambs of said 70 75

casing for selectively engaging said lock catch of said latch plate for preventing relative movement between said sash and said casing; an integral sleeve at the other end of said latch plate; and a pair of coaxial, oppositely wound coil springs extending through said sleeve for pivotally securing said latch plate to said mounting block and for biasing said plate to a position wherein said lock catch is disengaged from said flange means and projects beyond the inner peripheral border of said one of said stiles, the orientation of said pair of coil springs and said sleeve relative to said one of said stiles being such that said sleeve abuts said one of said stiles upon lateral deformation of said coil springs when said lock catch is engaged by said flange means.

7. A combined handle and latch for a sliding sash, comprising:

a latch plate; an integral sleeve at one end of said latch plate; a combined handle grip and lock catch at the other end of said latch plate and integral therewith; and a pair of oppositely wound coil springs in end-to-end abutment extending through said sleeve and pivotally securing said latch plate to said mounting block, the inner tail ends of said pair of coil springs being in abutment with said latch plate and applying a torque thereto.

8. An adjustable locking handle for a sash, comprising:

a mounting block; means coupled to said mounting block for securing said mounting block to the stile of a sash in sliding engagement therewith; a substantially planar latch plate; an integral sleeve carried at one end of said latch plate; a combined handle grip and lock catch carried at the other end of said latch plate and integral therewith; and a pair of coil springs extending through said sleeve for pivotally securing said latch plate to said mounting block and for applying a torque to said latch plate in prescribed direction.

9. In combination with a casing having head and sill members and a pair of jambs and a sliding sash including upper and lower rails and a pair of stiles, a latch mechanism comprising:

a latch plate; an integral, substantially cylindrical sleeve at one end of said latch plate, the walls of said sleeve defining an aperture extending along an axis substantially parallel to the stiles of said sash; a combined handle grip and lock catch, said lock catch having at least one projecting tooth parallel to said stiles; a pair of oppositely wound coaxial coil springs in end-to-end abutment within said aperture of said sleeve, the innermost spring tail ends abutting said latch plate and applying torque thereto about the common axis of said springs; a mounting block having sockets adapted to receive the outermost ends of said coil springs and to resist rotation of said springs about said common axis, said mounting block being seated within a longitudinal channel defined by the walls of one of said stiles; retaining means for maintaining said mounting block within said channel; and bead means projecting from the inner face of one of said jambs for selectively engaging said projecting tooth of said lock catch to restrain said sliding sash against movement relative to said casing.

10. A combination as set forth in claim 9, wherein said one of said stiles includes a retaining bead, and said retaining means includes a bow spring in engagement with said mounting block and said retaining bead.

11. A combination as set forth in claim 9, wherein said latch plate is substantially planar and the teeth project-

ing from said lock catch are canted with respect to the plane of said latch plate.
